J. A. FRASER.
LID OPENING DEVICE FOR GARBAGE CANS.
APPLICATION FILED SEPT. 1, 1911.

1,012,346.

Patented Dec. 19, 1911.

UNITED STATES PATENT OFFICE.

JAMES A. FRASER, OF FREEDOM, PENNSYLVANIA.

LID-OPENING DEVICE FOR GARBAGE-CANS.

1,012,346.

Specification of Letters Patent. Patented Dec. 19, 1911.

Application filed September 1, 1911. Serial No. 647,235.

To all whom it may concern:

Be it known that I, JAMES A. FRASER, a citizen of the United States of America, residing at Freedom, in the county of Beaver and State of Pennsylvania, have invented certain new and useful Improvements in Lid-Opening Devices for Garbage-Cans, of which the following is a specification, reference being had therein to the accompanying drawing.

10 This invention relates to lid opening devices for garbage cans, and the primary object of my invention is to furnish a garbage can with a foot actuating device that will permit of the lid of the can being easily and quickly opened when it is desired to deposit matter into the can.

15 I attain the above object by a device that is simple in construction, durable and inexpensive to manufacture.

The device obviates the necessity of a housewife setting down a receptacle containing garbage in order to use the hands to open the garbage can, as the device is constructed whereby a pressure of the foot will immediately open the lid of the can and the garbage can be deposited therein and the can immediately closed upon the foot releasing the device.

20 The invention will be hereinafter specifically described and then claimed, and reference will now be had to the drawing, wherein:

Figure 1 is a side elevation of the garbage can provided with the device, showing the lid of the can in a closed position, Fig. 2 is a similar view showing the lid in an open position, and Fig. 3 is a plan of the can and device.

25 A can in accordance with this invention comprises a bottom plate 1, a cylindrical shell 2, and a segment-shaped top plate 3. The top plate 3 partially closes the upper end of the shell 2 and the straight edge 45 of said top plate, at the ends thereof, is provided with barrels or apertured lugs 4. Arranged between these apertured lugs are the apertured lugs 5 of a lid or cover 6 adapted to close the remaining portion of 30 the upper end of the shell 2. The lugs 5 are mounted upon the ends of a crank shaft 7, the ends of said shaft extending through the lugs 4. The cranked portion 8 of the shaft 7 is loosely connected by a strap 9 to the lid or cover 6, adjacent to the straight edge thereof, said strap being riveted or

otherwise secured to the outer side of the lid cover, as at 10. The shaft 7 has a crank 11 at one end thereof and this crank has an eye 12 loosely connected to the upper end 60 of a rod 13. The lower end of the rod is loosely connected to an eye 14, carried by the rearward extension 15 of a semi-circular tread piece 16. Diametrically opposed sides of the tread piece 16 are pivotally 65 mounted upon trunnions 17, carried by the outer sides of the shell 2, adjacent to the bottom plate 1. The tread piece 16 is retained upon the trunnions 17 by cotter pins 18. Connecting the rearward extension 15 70 of the tread piece 16 and the bottom plate 1 is a coiled retractile spring 18^a normally retaining the lid or cover 6 in a closed position, as shown in Fig. 1. The semi-circular tread piece 16 has the treadle or foot portion 75 thereof retained in an elevated position, and when this treadle is trod upon, the spring 18^a is placed under tension, the rod 13 elevated, and the shaft 7 moved to open the lid or cover 6. As long as the pressure of 80 the foot remains upon the tread piece 16, the lid will be open, but upon the foot releasing the tread piece, the coiled retractile spring 18 immediately restores the lid to a closed position and the parts of the opening 85 device to their normal position. Diametrically opposed sides of the shell 2 have suitable handles 19.

The lid opening device in its entirety is made of light and durable metal, and with 90 the semi-circular tread piece 16 surrounding the front side of the can, it is possible to open the lid or cover of the can without necessarily standing directly in front of the same.

95 What I claim is:—

The combination with a garbage can having a top plate partially closing the top thereof of a lid for closing the remaining portion of said top, a keeper secured to the upper face of said lid, vertically disposed apertured lugs carried by said lid and plate and arranged at each side of said plate and lid, said lugs positioned in alinement, a crank shaft having one end extending 100 through and projecting from said lugs and its crank portion mounted in said keeper, said shaft and lugs constituting means for hinging the lid to said plate, a crank depending from the projecting end of said 105 shaft, a rod having the upper end thereof pivotally connected to said depending crank, 110

a tread piece having one end pivotally connected to said can and its other end pivotally connected to the lower end of said rod, means for pivoting said tread piece to the can at a point removed from the connection between the tread piece and said rod, and a spring connected at one end to said tread piece in proximity to the lower end

of said rod and having its other end connected to the can.

In testimony whereof I affix my signature in the presence of two witnesses.

JAMES A. FRASER.

Witnesses:

JOSEPH FRASER,

WILLIAM JOLLEY.
